SPOOL HANDLING APPARATUS

Homer P. Lane, Indianapolis, Ind., assignor to Western Electric Company, Incorporated, a corporation of New York

Filed July 24, 1961, Ser. No. 126,030
5 Claims. (Cl. 242—129.7)

This invention relates to apparatus for handling spools, and more particularly to apparatus for positioning and releasably holding a plurality of spools in axial alignment and in axially spaced relationship to facilitate simultaneous rotation of the spools for the winding of material thereon. It is an object of the invention to provide improved apparatus of such character.

Conventionally, mass winding of wire coils is accomplished through simultaneous winding of a plurality of wires on a common mandrel or spool, following which the spool is severed between coils such that the coils are separated. While this method has the advantage of employing the simplest possible form of spool and of requiring the simplest possible manipulation of wire and insulating sheets, it has the disadvantage that the resulting coils are not as mechanically stable as a coil which has been wound on a headed spool. A major factor dictating against the use of headed spools for coils is the high cost which has attended the individual handling of the headed spools in preparation for the winding operation.

It is another object of the invention to provide apparatus for facilitating the arrangement of individual headed spools for the winding of material thereon.

It is still another object of the invention to provide improved apparatus for facilitating the positioning and for releasably holding a plurality of spools in axial alignment and in axially spaced relationship to facilitate simultaneous rotation of the spools for the winding of material thereon.

In accordance with the present invention, a spindle is provided having a housing of generally rectangular cross section for receiving the spools thereon. A rod is arranged within an axial passage in the housing and is rotatable therein. Pins extend radially from the rod and through circumferentially extending slots in the spindle housing. The pins are of such length that when the rod is rotated to orient the pins parallel to one surface of the spindle housing, the pins extend substantially beyond the outer surface of the housing such that they limit axial movement of the spools on the housing and space the spools axially apart. However, when the rod is rotated to orient the pins along a diagonal of the rectangular cross section of the spindle housing, the pins are substantially retracted within the housing such that spools may be moved onto or off the spindle housing. Preferably, the pins are arranged in radially opposed pairs, that is in pairs of which the two pins extend in radially opposite directions. This provides for two pins to be arranged between the heads of adjacent spool heads. Also, the pins are preferably in the form of hooks in order to facilitate control of filamentary material such as a wire which is to be wound on the spools. Still further, a rack is preferably provided having parallel slots for receiving portions of the spool heads with the spools arranged in axial alignment and in axially spaced relationship. This rack facilitates the original arranging of the spools in the desired relative orientation and positions, whereby the spindle may readily be inserted into the cores of the spools with its pins retracted, and the pins may readily be extended into the space between the spools in the rack.

This invention, together with further objects and ad-

2

vantages thereof, will best be understood by reference to the following description taken in connection with the accompanying drawings, in which

FIG. 1 is a side elevational view of a spindle illustrating one embodiment of the invention;

FIG. 2 is a cross-sectional view taken along the line 2—2 of FIG. 1;

FIG. 3 is a fragmentary perspective view of the spindle of FIGS. 1 and 2 with spools arranged thereon;

FIG. 4 is a plan view of a rack for facilitating proper positioning and orienting of spools, a number of spools being shown in proper position in the rack; and

FIG. 5 is a partial cross-sectional view taken along the line 5—5 of FIG. 4.

15 The spindle shown in FIGS. 1, 2 and 3 includes a spindle housing 11 which is of generally rectangular cross section. A cylindrical bore 12 extends substantially through the length of the spindle housing and opens through at least one end thereof. Arranged with the bore 12 and rotatable with respect to the housing 11 is a rod 13. One end of the rod extends beyond the end of the housing as seen in FIG. 1.

A plurality of pins 15 are threadedly received in the rod 13 and extend radially therefrom. Preferably, these pins are arranged in radially opposed pairs, that is, in pairs of which the two pins extend in radially opposite directions as is clearly shown in FIG. 2. Slots 16 are provided in the spindle housing 11 to accommodate the pins 15. These slots are of such width as to receive the pins freely. Each slot also extends circumferentially through an arc of such magnitude that the rod 13 may be rotated through such an angle that the pins are moved from a position in which they are parallel to the narrow sides of the housing (the position shown in solid lines in FIG. 2) to a position in which they extend along a diagonal of the rectangular cross section of the housing (the position shown in phantom lines in FIG. 2).

Upon reference to FIG. 2, it may be noted that the pins 15 are of such length that when they are in their phantom line positions they are retracted within the spindle housing, and when they are in their solid line positions they extend substantially beyond the outer surface of the spindle housing. In the latter positions the pins may engage and limit axial movement of spools which are arranged on the spindle housing. They also may serve to space such spools axially apart, all as best illustrated in FIG. 3.

In the illustrated embodiment of the invention, the pins 15 are in the form of hooks. As will be apparent to those skilled in the art, these hooks may be used to advantage in the handling of the wire or other filamentary material which is to be wound on the spools. More particularly, the wires extending from the supply to a group of wound spools, still supported on one spindle, may be caught on the hooks 15 of a spindle which supports empty spools, whereby the wires may be properly positioned for the initiation of winding onto the fresh spools. Following this operation, the wires may be cut at any suitable points between the wound spools and the fresh spools. For this purpose, it may be preferred that the pins, or hooks 15, extend radially beyond the heads of the spools.

In order to facilitate the arrangement of the spools on the spindle, the spools may first be arranged in the rack 20 shown in FIGS. 4 and 5. This rack has parallel slots 21 which are of such length and are so spaced apart that adjacent ones may receive portions of the two heads of a spool. The slots are of such width that each may receive portions of one head of each of two spools with the spools axially spaced apart.

70 It will be apparent that a plurality of spools may quickly be brought into the desired position and orienta-

tion wherein they are axially aligned and axially spaced through use of the rack 20. With a plurality of spools thus oriented and positioned, the spindle may be inserted into the cores of the spools with the pins 15 in their retracted positions. With the spindle fully inserted, the exposed end of the rod 13 may be rotated through a small angle to bring the pins 15 to their extended positions, this being permitted by the fact that the spools are held in properly spaced positions by the rack 20. The spindle with the associated spools may then be removed from the rack and placed in a spool winding machine.

When it is subsequently desired to remove the spools from the spindle, it is necessary only to rotate the exposed end of the rod 13 such that the pins 15 are moved to their retracted positions. The spools may then readily be slid off the spindle.

It will be noted that the spools which are illustrated in the drawings have cores which are rectangular both with respect to the bore therethrough and the exterior winding surface. It will be appreciated that a rectangular configuration of the core is desired in the present application only for the purpose of preventing relative rotation of the spindle and the spools. The spools may, if desired, have a circular, exterior or winding surface. Still further, the interior bore of the spools may be substantially circular and provided with protrusions or recesses which define a rectangle such that the spools are non-rotatable with respect to the spindle. Where a rectangular cored spool is referred to herein it is intended that the phrase be interpreted broadly to refer to any spool which is made non-rotatable with respect to a spindle of generally rectangular cross section through provision of bore-defining portions which cooperate suitably for this purpose with the spindle.

It will now be seen that new and improved apparatus has been illustrated and described for facilitating the handling of individual spools, and in particular for positioning and for releasably holding a plurality of spools in axial alignment and in axially spaced relationship to facilitate simultaneous rotation of the spools for the winding of material thereon. As will be apparent to those skilled in the art, the illustrated and described apparatus is simple in construction and reliable and efficient in operation.

While a single embodiment of the invention has been disclosed, many modifications will be apparent, and it is intended that the invention be interpreted as including all modifications which fall within the true spirit and scope of the invention.

What is claimed is:

1. A spindle for releasably holding a plurality of spools in axial alignment and in axially spaced relationship and for facilitating simultaneous rotation of the spools for winding of material thereon, said spindle comprising an elongated housing of generally rectangular cross section for receiving the spools thereon, said housing having a passage therein extending longitudinally thereof, a rod arranged within said passage and rotatable with respect to said housing, a plurality of circumferentially extending slots in said housing opening into said passage and through the outer surface of the housing, and a plurality of pins rigidly secured to and extending radially from said rod within said slots, said pins being of such length that they extend substantially beyond the outer surface of said housing to limit axial movement of the spools and to space the spools axially apart when said pins are oriented to extend parallel to one outer surface of said housing, and to

be substantially retracted within said housing when oriented to extend along a diagonal of said housing.

2. A spindle as specified in claim 1 wherein said pins are of such dimension axially of said rod as to substantially fill the width of said slots.

3. A spindle as specified in claim 1 wherein each of said pins is in the form of a hook, thereby to facilitate control of filamentary material to be wound on the spools.

4. A spindle for releasably holding a plurality of spools in axial alignment and in axially spaced relationship and for facilitating simultaneous rotation of the spools for winding of material thereon, said spindle comprising an elongated housing of generally rectangular cross section for receiving the spools thereon, said housing having a passage therein extending longitudinally thereof, a rod arranged within said passage and rotatable with respect to said housing, a plurality of circumferentially extending slots in said housing opening to said passage and through the outer surface of the housing, said slots being arranged in radially opposed pairs, and a plurality of pins rigidly secured to and extending radially from said rod within said slots and arranged in radially opposed pairs, said pins being of such length that they extend substantially beyond the outer surface of said housing to limit axial movement of the spools and to space the spools axially apart when said pins are oriented to extend parallel to one outer surface of said housing, and to lie substantially within said housing when oriented to extend along a diagonal of said housing.

5. Apparatus for positioning and for releasably holding a plurality of spools in axial alignment and in axially spaced relationship and for facilitating simultaneous rotation of the spools for winding of material thereon, said apparatus comprising an elongated spindle housing of generally rectangular cross section for receiving the spools thereon, said housing having a passage therein extending longitudinally thereof, a rod arranged within said passage and rotatable with respect to said housing, a plurality of circumferentially extending slots in said housing opening

into said passage and through the outer surface of the housing, a plurality of pins rigidly secured to and extending radially from said rod within said slots, said pins being of such length that they extend substantially beyond the outer surface of said housing to limit axial movement of the spools and to space the spools axially apart when said pins are oriented to extend parallel to one outer surface of said housing, and to be substantially retracted within said housing when oriented to extend along a diagonal of said housing, and a rack having a plurality of parallel slots of such length and so spaced apart as to permit reception of portions of the two heads of a spool in two adjacent ones of said slots, thereby to orient and position the spool, each slot being of such width as to permit reception of portions of one head of each of two spools in axially aligned and axially spaced relation, whereby said spindle housing may readily be inserted into the cores of spools arranged in said rack with said pins retracted, and said pins may readily be extended into the slots in said rack between the spools.
